(57) **CLAIM**

The ornamental design for a shipping pallet, as shown and described.

DESCRIPTION

FIG. 1 is an isometric view of a shipping pallet from above, showing our new design;

FIG. 2 is an isometric view of the pallet from below;

FIG. 3 is a left side elevation view;

FIG. 4 is an upper side elevation view;

FIG. 5 is a right side elevation view;

FIG. 6 is a lower side elevation view;

FIG. 7 is a top plan view; and,

FIG. 8 is a bottom plan view.

The broken lines in the figures are included for the purpose of illustrating portions of the pallet and form no part of the claimed design.
